DANIEL L. WERTZ, OF ELMIRA, NEW YORK, ASSIGNOR TO ECLIPSE MACHINE COMPANY,
OF ELMIRA, NEW YORK, A CORPORATION OF NEW YORK

REBOUND CHECK FOR STARTER PINIONS

Application filed April 27, 1932. Serial No. 607,836.

This invention relates to a rebound check for starter pinions and more particularly to a combined anti-drift and rebound check for normally keeping a starter pinion in idle 5 position.

In starter drives of the type in which a driving pinion is automatically traversed into and out of mesh with a gear of the engine to be started, there is sometimes a tendency for the pinion to move over and contact the engine gear when the engine is running. This may be caused by the vibration of the engine or may occur by reason of the rebounding of the pinion when thrown out 15 of mesh as the engine starts, and in either case may cause unnecessary noise and wear of the parts.

It is an object of the present invention to provide a novel rebound check and anti-drift 20 which is simple and economical in construction while being efficient and reliable in operation.

It is a further object to provide such a device which is readily adaptable to existing 25 types of starting mechanism.

Further objects and advantages will be apparent to those skilled in the art from the following description taken in connection with the accompanying drawing in which:

30 Fig. 1 is a side elevation of a starter drive showing a preferred embodiment of the invention;

Fig. 2 is an enlarged detail partly in section showing the rebound check in active position; and

Fig. 3 is a view similar to Fig. 2 showing the positions of the parts when the pinion is being traversed toward driving position.

Referring first to Fig. 1 of the drawing 40 there is illustrated a power shaft 1 which may be the extended armature shaft of the starting motor, not shown. An operating member in the form of a screw shaft 2 is slidably journaled on the power shaft and is connected 45 to rotate therewith by means of a yielding driving connection including a torsion spring 3 anchored at its ends to said shaft as indicated at 4 and 5 respectively.

50 A driving member in the form of a pinion 6 is threaded on said screw shaft in position

to be traversed thereby into and out of mesh with a member of an engine to be started such as a flywheel gear, a fragment of which is indicated at 7.

Means for yieldingly opposing longitudinal movement of the driving member away from idle position is provided in the form of a yielding detent comprising a plunger 8 (Figs. 2 and 3) mounted to be radially slideable in a counter-weight flange 9 suitably fixed on the pinion 6 in position to bear on screw shaft 2 at the rear of an inclined shoulder 10 thereon when the pinion is in idle position. Means for yieldingly urging the detent 8 into engagement with the screw shaft 65 is provided in the form of a spring 11 bearing against the head 12 of the detent.

Means for arresting the longitudinal movement of the driving member into idle position and at the same time increasing the pressure 70 of the detent 8 against the screw shaft in order to prevent rebounding of the pinion is illustrated in the form of a clip or lever 13 one arm 14 of which is located within the flange 9 of the pinion and is traversed by 75 the detent 8, while the opposite arm 15 extends rearwardly at an oblique angle thereto in position to be engaged by a flange 16 on the screw shaft when the pinion is in idle position, the spring 11 being arranged to bear on 80 the arm 14 of lever 13 whereby when the lever is tilted by the engagement of the arm 15 with flange 16, the spring 11 will be compressed as shown in Fig. 2.

In operation, rotation of the power shaft 85 1 is transmitted to the operating shaft 2 in the direction of the arrow, whereupon the pinion 6 by reason of its inertia will be translated to mesh with the engine gear 7, the detent 8 riding up the shoulder 10 on the screw 90 shaft without undue resistance since the spring 11 is then exerting merely its normal moderate pressure. When the engine starts, the acceleration of the engine gear causes the pinion to overrun the screw shaft and be 95 translated thereby back to idle position. This rearward translation may take place with considerable violence but the arm 15 of detent 8 is arranged to engage the flange 16 on the screw shaft and check the rearward mo- 100

tion of the pinion while increasing the frictional engagement of the detent 8 with the screw shaft by reason of the tightening of the spring 11 as shown in Fig. 2. This increased pressure of the detent is arranged to prevent the pinion from bounding back toward the engine gear, but the angle of the threads on the operating shaft 2 is sufficiently high so that the parts do not wedge when the pinion is thrown against the flange 16.

Although but one embodiment of the invention has been shown and described in detail it will be understood that other embodiments are possible and that changes may be made in the arrangement and construction of the parts without departing from the spirit of the invention as defined in the claims appended hereto.

What is claimed is:—

1. In an engine starter drive, an operating shaft, a driving member mounted on said shaft for longitudinal movement thereof into and out of engagement with a member of the engine to be started, and for rotation therewith to crank said engine, means for yieldingly opposing longitudinal movement of the driving member away from idle position and means for arresting longitudinal movement of the driving member into its idle position, said arresting means being arranged when operative to increase the effectiveness of the yielding opposing means.

2. In an engine starter drive, an operating shaft, a driving member mounted on said shaft for longitudinal movement into and out of engagement with a member of an engine to be started and for rotation therewith to crank the engine, a detent on said driving member for opposing longitudinal movement of the driving member away from idle position and means for yieldingly arresting longitudinal movement of the driving member into its idle position, said arresting means being arranged when operative to increase the effectiveness of said detent.

3. In an engine starter drive, an operating shaft, a driving member mounted on said shaft for longitudinal movement into and out of engagement with a member of an engine to be started and for rotation therewith to crank the engine, a spring pressed detent on said driving member adapted to frictionally engage said shaft and means including abutment elements for arresting longitudinal movement of the driving member into its idle position and for concurrently increasing the pressure of said detent on said shaft.

4. In an engine starter drive, an operating shaft, a driving member mounted on said shaft for longitudinal movement into and out of engagement with a member of an engine to be started and for rotation therewith to crank the engine, a spring pressed detent on said driving member adapted to frictionally engage said shaft, a stop shoulder on said shaft

adjacent the idle position of the driving member and a lever carried by said driving member having one arm engaging the detent spring and the other arm arranged to engage said shoulder when the pinion is returned to idle position whereby said lever is operated to increase the pressure of the detent spring.

In testimony whereof, I have hereunto signed my name.
